UNITED STATES PATENT OFFICE.

CLAUDE L. POST, OF CHICAGO, ILLINOIS.

ENVELOPE FEEDER.

Application filed March 19, 1924. Serial No. 700,403.

My invention relates to improvements in mechanism for feeding envelopes, and particularly to such mechanism for use in conjunction with a printing press or the like, 5 wherein it is desired to feed sheets, envelopes, etc., at a high rate of speed through said press.

One of the objects of my invention is to provide means for automatically preventing 10 contact between the platen and the type of the press whenever there is no envelope or sheet passing through the press.

Another object of my invention is to provide a new and improved means of feeding 15 the envelopes from the magazine to the rolls and maintaining said envelopes in absolute registry with the rolls during the feeding thereto.

Many other objects and advantages of the 20 construction herein shown and described will be obvious to those skilled in the art from the disclosure herein given.

To this end my invention consists in the 25 novel construction, arrangement and combination of parts herein shown and described, and more particularly pointed out in the claims.

In the drawings, wherein like reference 30 characters indicate like or corresponding parts,

Fig. 1 is a top plan view of my improved device;

Fig. 2 is a sectional view of the same taken substantially on line 2—2 of Fig. 1;

Fig. 3 is a fragmentary plan view of the platen and type rolls showing the means for preventing contact therebetween when there is no envelope passing between the rolls;

Fig. 4 is a section taken substantially on line 4—4 of Fig. 3;

Fig. 5 is a section taken substantially on line 5—5 of Fig. 4;

Fig. 6 is a perspective view of the locking 45 arm or catch member;

Fig. 7 is a radial cross-section through the driving wheel, taken on the line 7—7 of Fig. 8;

Fig. 8 is a longitudinal section of the same, 50 taken substantially on the line 8—8 of Fig. 7;

Fig. 9 is a plan view of one of the adjustable bottom plates for the envelope magazine; and

Fig. 10 is a plan view of the cooperating 55 adjustable bottom plate.

In the preferred form of construction, as

shown in the drawings, I have shown the device as used in connection with a press for feeding envelopes from a magazine, conveying them between a pair of feed rolls 60 and thence discharging them at the rear of the press. It is to be understood, however, that my device is not limited to envelopes, but may be used for feeding any other similar objects or materials, such as sheets or 65 the like.

1 represents a supporting frame for the printing mechanism, the same suitably supported so as to be of the correct height for most efficient operation. The envelopes are 70 retained in a magazine 2 and are fed from the bottom, one at a time, automatically through printing rolls and are then discharged therefrom for removal. The printing rolls comprise a pair of rolls 3 and 4 75 respectively, the former being the type roll and the latter the platen roll, and through which the envelopes must pass to be imprinted. These rolls are driven positively in unison through any form of gearing or 80 the like, and in any desired manner, both of said rolls rotating at the same rate of speed.

In the particular device shown, the drive 85 shaft 5 has a friction wheel 6 thereon, engageable with a disk 7, which, in turn, is 90 drivingly connected to the gears carried by the rolls 3 and 4. The friction wheel 6 is adjustable radially of the disk, so that the driving speed of the disk may be regulated as desired.

It is to be noted that the platen roll 4 has the ends of its shaft 8 mounted in eccentrically bored bushings, as shown more clearly in Fig. 4, for a purpose to be more 95 clearly hereinafter described.

The magazine 2 comprises a pair of adjustable base plates 9 and 10, there being upright side walls 11 adjustably positioned so that the magazine may receive any size of envelope therein. There is also a front wall 100 11^a which has its lower edge spaced a slight distance above the base plates to permit an envelope to be fed from the magazine. The base plates 9 and 10 have elongated bolt receiving fastening slots 12 therethrough 105 so that they may be adjustably positioned on the frame-work supporting the magazine. Thus the magazine or envelope receptacle may be adjusted for various lengths of envelopes. The forward edges of the 110 bottom plates 9 and 10 are cut away so as to form a substantially triangular recess for

receiving the envelope flap so that the envelope may pass outwardly from the magazine through said opening. One of the plates, as for instance the plate 10, is cut back farther than the other plate, as at 13 so that a flap-engaging finger, movable below said magazine to engage the envelopes, may always clear the plates and be sure to contact with the body of the envelope behind the flap portion and extend the flap forwardly.

The magazine is preferably removably arranged on the frame at a distance away from the printing rolls, and a finger 14, operated in any desired manner, is positioned adjacent the discharge end of the magazine to engage the flaps of the envelopes and extend said flaps forwardly toward the printing rolls so that they may be frictionally held between the peripheral surfaces of feed rolls 15 and 16, respectively, and pulled therethrough in the direction of the printing rolls, said feed rolls being positively driven.

In order to convey the envelopes positively as they are discharged from the feed rolls and deliver them to the printing rolls, while at the same time centering the envelopes, I have provided a pair of channel guides 17 to receive the side edges of the envelopes and support the envelopes during their travel to the printing rolls. These guides 17 are adjustable to accommodate envelopes of various lengths. Intermediate the side guides, I arrange spaced guides 37 to receive the flap portions of the envelopes.

In order to more positively actuate the envelopes during their travel, belt conveyors 18 are arranged beneath the centering channels and have lugs 19 spaced thereon at suitable intervals to engage the rear edges of the envelopes and convey or push them along. Adapted to cooperate with the roll 16, and drivingly connected therewith by a belt or chain 20, is a roll 21, whereby the envelopes are pressed downwardly and firmly held on the conveyor during travel through the guides.

The envelope at the bottom of the magazine has its flap extended forwardly by the finger 14 so that the flap is gripped between the feed rolls 15 and 16 and thence moved through the channeled guides, the chain 20 pressing the envelopes downwardly until one of the lugs 19 engages the rear edge of the envelope and pushes the envelope past the roll 21, where said extended flap of the envelope is gripped between the rotating platen and type roll and is imprinted in its passage therethrough. Wheels 38 having forwardly extending teeth thereon, are carried on the lower chain drive shaft most closely adjacent the magazine, one wheel on each side of the chain 20, so that in case the forward edge of the extended flap of an envelope fed through the rolls 15-16 is curled, the rotating wheels 38 will engage said curled por-

tion and extend it so that it will enter the flap guides 37 without any buckling.

In order that the type roll and platen shall not come together whenever there is no envelope being fed therethrough, the roll 4 is mounted in the eccentric bushings 9', as previously described. Connected to one of these bushings, as shown more clearly in Fig. 4, is a lever 22, so that when the lever is rocked or pivoted, the bushing will be oscillated to lower the rotational axis of the shaft 8 and thus separate the rolls 3 and 4.

For actuating the eccentric journals simultaneously, a gear segment 23 is operatively connected to the lever 22 and is adapted to mesh with a pinion 24 mounted on a shaft 25 extending across the frame 1, the other end of the shaft 25, having a pinion thereon similar to the pinion 24 and intermeshing with a gear segment thereat rigidly connected to the eccentric bushing at the adjacent end of the shaft 8.

A cam member 26 is drivingly connected to the shaft of the roll 3, but is slidable longitudinally thereof, said cam being of such a contour that it will operate the lever 22 only when rotating in the same plane therewith. In this instance, the cam 26 is rigidly secured by screws 26^a or the equivalent to a disc 26^b mounted on the shaft 3, which disc may be considered as part of the cam as they are constrained to move as a single unit longitudinally of the shaft 3. An abutment or stationary cam 27 is carried on the frame 1 to engage the rotary cam 26 and retrieve said cam out of registry with the lever 22, but guiding said cam into registry therewith whenever said slidable cam is moved longitudinally of the shaft of the type roll 3 (to the right). A coiled spring 28 is interposed between the disc 26^b and the adjacent end of the type roll, in order to constantly urge the rotary cam to the right and into operative engagement with the lever 22.

As the lever 22 is intended to be oscillated only when there are no envelopes passing through the printing rolls, means must be provided for normally preventing such operation and for automatically moving said cam to actuate the lever when the passage of envelopes is interrupted. For this purpose a slotted lug, or pin 29 is fixed to the disc 26^b, the slot therein being indicated at 30. This pin is rigidly carried by the disc and projects inwardly of the inner side thereof.

A rocker shaft 31 is mounted on the stationary framework adjacent the printing rolls, and intermediate the ends of said rocker shaft there is carried an arm 32 which extends in the path of envelopes passing to the printing rolls, the shaft 31 being freely mounted in its end bearings so that when an envelope is passing beneath the arm 32, said arm will be raised or lifted by the envelope, and when there is no envelope

beneath the arm, it will drop, due to gravity and rock the shaft 31.

A lever or arm 33 is carried by the rock shaft 31 adjacent the rotatable cam 26 and is adapted to engage with a catch or lock member or arm 34 pivotally carried by the roll 3, shown more clearly in Figs. 3, 4 and 6. The width of the catch member 34 is such that it may enter the slot 30 formed in the pin 29 and hold the cam member 26 in its retrieved position against the outwardly exerted pressure of the spring 28.

The operation of the means for separating the printing roll is as follows:

Assuming that there is no envelope in readiness for insertion between the printing rolls and that the rolls are rotating, it will be seen that the spring 28 constantly presses the rotary cam toward the stationary cam. The arm 33 will then be in the position indicated by dotted lines in Fig. 4. The continued rotation of the cam will cause it to slide off the stationary cam and engage with the rocker arm to actuate it to cause separation of the rolls. On account of the centrifugal force the locking pin 34 will be thrown out of the slot 30 and the cam 26 will be released thereby to actuate the eccentric bushings. A spring 35 may be positioned to engage the arm 22 to return it to its normal position after each actuation thereof.

When there is no envelope between the rolls, the catch 34 hits the arm 33, which is then in the position shown in dotted lines at 33 in Fig. 4, but the catch is not moved sufficiently on its pivot to re-engage in the slot 30, and thus the cam 26 will not be locked, but will ride over the cam 27 to the crest of said cam and be again moved to its retrieved position, shown in full lines in Fig. 3, whereupon in case there is still no envelope in position to pass through the printing rolls, the catch will again hit the arm 33 but fail to enter the slot, and the printing rolls will again separate. As soon as an envelope is in position for insertion between the rolls, the envelope-supported arm 32 will be lifted to rock the arm 33 to the full line position shown in Fig. 4, whereupon it may engage with the catch 34, this time causing said catch to enter into the slot and retain the movable cam locked in its retrieved position. Thus in each rotation of printing rolls, the latch is released through centrifugal force and in case the feed of envelopes is uninterrupted the lock will be pressed back into the slot just as the rotary cam is at the end of its ride over the stationary cam and again lock said cam in place. However, in case the feed of envelopes is interrupted, the released latch will not be pushed back into the slot but will remain free until it again engages the arm 33, whereupon it will be either lifted to its unlatched position or will be lifted to its latched position in the slot, depending

upon whether or not there is or is not an envelope beneath the arm 32.

In order to simplify the method of keying the friction wheel 6 slidably on the shaft 5, I have arranged a collar 40 to be keyed through the hub of said friction wheel, as shown more clearly in Figs. 7 and 8. The hub 41 has a slot cut through the wall thereof from one end as at 42, in registry with the key-way 43 in the shaft 5. The collar 40 is bored to be mounted on the sleeve or hub 41, the bore being recessed or cut back at one point so as to form a substantially wide shallow groove or slot through the collar. A key is formed of a narrow piece of material of a sufficient thickness to enter through the registering slots 42 and 43, as at 45, the key then being bent laterally at one end to form a leg 46 adapted to be received within the slot 47 cut back from the bore of the collar.

A set screw 48 is arranged radially of the collar and is tightened down onto the key to hold it in place more securely. If desired, additional set screws 49 may be employed. This key is very easy to remove from the shaft when it is necessary to do so, as it can be easily gotten at when the collar is slid off the hub 41. A shifting lever 50 is loosely connected on the hub of the friction disk so as to shift the same axially of the shaft 5.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. The combination with a pair of rolls, of means for separating said rolls whenever there is no material being fed thereto, a rotatable cam for actuating said separating means, yielding means for bringing said cam into a position wherein it will actuate said separating means, and means outside of said rolls and controlled by the material passing to said rolls for preventing said yielding means from bringing said cam into said position.

2. The combination with a pair of rolls, of means for separating said rolls whenever there is no material being fed thereto, a rotatable cam for actuating said separating means, said cam being constrained to rotate with one of said rolls and having an axis of rotation coincident therewith, yielding means for bringing said cam into a position wherein it will actuate said separating means, and means spaced from the rolls and controlled by the material passing to said rolls for preventing said yielding means from bringing said cam into said position.

3. The combination with a pair of rolls,

of means for separating said rolls whenever there is no material being fed thereto, a cam constrained to rotate in unison with one of said rolls for actuating said separating means, mechanism for bringing said cam into a position wherein it will actuate said separating means, and means controlled by the material passing to said rolls for preventing said mechanism from bringing said cam into said position.

4. The combination with a pair of rolls, of means for separating said rolls whenever there is no material being fed thereto, a cam constrained to rotate in unison with one of said rolls for actuating said separating means, an element for bringing said cam into a position wherein it will actuate said separating means, and means including a member rotatable bodily with the cam for preventing said element from bringing said cam into said position.

5. The combination with a pair of rolls, of means for separating said rolls whenever there is no material being fed thereto, a cam constrained to rotate in unison with one of said rolls for actuating said separating means, resilient means for bringing said cam into a position wherein it will actuate said separating means, and means including a member rotatable bodily with the cam for preventing said resilient means from bringing said cam into said position.

6. The combination with a pair of rolls, of means for separating said rolls whenever there is no material being fed thereto, a cam constrained to rotate in unison with one of said rolls for actuating said separating mechanism, yielding means for bringing said cam into a position wherein it will actuate said separating mechanism means for preventing said yielding means from bringing said cam into said position, and a stationary cam for displacing the first mentioned cam against the action of said yielding means.

45 7. The combination with a pair of rolls, of means for separating said rolls whenever there is no material being fed thereto, a cam having an axis of rotation coincident with that of one of said rolls and being constrained to rotate with said roll, yielding means for bringing said cam into a position wherein it will actuate said separating means, a member carried by said cam and rotatable bodily therewith, a second member

constrained to rotate bodily with that roll which has its axis of rotation coincident with that of the cam, and means controlled by the material passing to said rolls for causing said second member to engage first mentioned member to prevent said yielding means from bringing said cam into said position.

8. The combination with a roll, of a second roll, bearings for said rolls, means for eccentrically journaling the bearings for said second roll, means for displacing said last mentioned means to separate said rolls whenever there is no material being fed thereto, a rotatable cam for actuating said separating means, yielding means for bringing said cam into a position wherein it will actuate said separating means, and means controlled by the material passing to said rolls for preventing said yielding means from bringing said cam into said position.

9. In combination with a pair of rolls, means for separating said rolls whenever there is no material fed therethrough, a rotary cam, a latch normally holding said cam inoperative for actuating said separating means, a lever arm pivotally mounted in the path of said material, and a second arm rigidly connected to said first-mentioned lever arm so as to be actuated thereby and arranged adjacent said cam and operably engageable with said latch.

10. In combination with a pair of rolls, means for separating said rolls whenever there is no material being fed therethrough, a cam carried by one of said rolls, a slotted pin on said cam, a latch member movably mounted on said cam-carrying roll to engage in the slot of said pin to hold it in its inoperative position, a lever arm adjacent said rolls in the path of said material, a rock shaft fixed at one end of said arm, a second lever arm fixed to the other end of said rock shaft adjacent said latch member and operably engageable therewith when there is material passing to said rolls to move said latch member into said slot and to fail to move said last-mentioned member therein when there is no material passing to said rolls.

In testimony whereof, I have hereunto signed my name.

CLAUDE L. POST.
